His ATTORNEY.

UNITED STATES PATENT OFFICE

JOHN W. LIVINGSTON, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY CAR RETARDER

Application filed September 2, 1931. Serial No. 560,718.

My invention relates to railway car retarders, and particularly to car retarders of the track brake type used in classification or hump yards of railroads for controlling the speed of cars.

One object of my invention is the provision of improved automatic apparatus for controlling the braking action of a car retarder of the type described in accordance with the speed of cars approaching or passing through the retarder. Specifically, the present invention is an improvement on apparatus of the type disclosed and claimed in an application for Letters Patent of the United States, filed by Herbert L. Bone on July 9, 1931, Serial No. 549,588, for railway braking apparatus.

I will describe one form of car retarder controlling apparatus embodying my invention, and will then point out the novel features thereof in claims.

The accompanying drawing is a view, partially sectioned and partially diagrammatic, illustrating one form of apparatus embodying my invention.

Referring to the drawing, the reference characters 1 and 1^a designate the track rails of a stretch of railway track over which cars normally move in the direction indicated by the arrow under such conditions that it is desirable to control the speed of the cars. For example, the stretch of track here shown might be in a classification yard of the "hump" type through which cars move under the influence of gravity. It is obvious that in service of this kind, the speed of individual cars or strings of cars will vary through wide limits depending, among other things, upon the speed at which they go over the hump, the temperature, the weight of the car and contents, and the condition of the car as to whether it is a free running car or otherwise.

In order to control the speed of the cars, the stretch of track illustrated in the drawing is provided with a car retarder R which, in the form here shown, comprises two braking bars 2 and 3, extending parallel with and located on opposite sides of rail 1, and two similar braking bars 2^a and 3^a extending parallel with, and located on opposite sides of rail 1^a.

The braking bars 2, 3, 2^a and 3^a are operated by a fluid pressure motor M comprising a cylinder 4 containing a reciprocable piston 5 attached to one end of a piston rod 6. The braking bars 2, 3, 2^a and 3^a are operatively connected with the piston rod 6 through suitable linkwork including a bell crank 7 and a lever 8 pivotally supported at point 9. When piston 5 occupies its extreme right-hand position, in which it is illustrated in the drawing, the braking bars occupy their non-braking or ineffective positions in which they are out of engagement with the wheels of a car traversing rails 1 and 1^a. When piston 5 is moved to its left-hand position, however, as when fluid pressure is admitted to the right-hand end of cylinder 4, the braking bars 2, 3, 2^a and 3^a are moved toward the associated rail to their effective or braking positions in which they will engage the wheels of a car traversing the rails 1 and 1^a, to retard the speed of the car.

The motor M is controlled by two magnet valves V¹ and V², each comprising a valve stem 10 biased to an upper position by means of a spring 11, and each provided with a winding 12 and an armature 13. When winding 12 of valve V¹ is deenergized, as shown in the drawing, valve stem 10 of this valve is moved to its upper position by the spring 11, and under these conditions, the right-hand end of cylinder 4 is connected with atmosphere through a pipe 14 and a port 15. When winding 12 of this valve is energized, however, valve stem 10 is moved downwardly against the bias of spring 11 to disconnect pipe 14 from atmosphere, and to connect this pipe with a suitable source of fluid pressure, usually air, through a pipe 16. When winding 12 of valve V¹ is energized, therefore, the fluid pressure supplied to the right-hand end of cylinder 4 moves piston 5 toward the left, thereby moving the braking bars to their effective or braking positions.

When winding 12 of valve V² is deenergized, valve stem 10 of this valve is moved to its upper position, and the left-hand end of cylinder 4 is then connected with atmosphere through a pipe 17 and a port 18. When winding 12 of valve V² is energized, however,

as shown in the drawing, valve stem 10 is moved downwardly, disconnecting pipe 17 from port 18, and connecting pipe 17 with pipe 16. It will be apparent, therefore, that when valve V^2 is energized, piston 5 is urged toward the right, thus holding the braking bars in their ineffective or non-braking positions.

The magnet valves V^1 and V^2 are controlled by means of a normally deenergized control relay C, and by a manually operable lever L. The lever L, in the form here shown, is capable of assuming a left-hand position *a*, in which it is illustrated in the drawing, and a right-hand position *b*, indicated by a dotted line in the drawing. Operatively connected with the lever L is a contact arm 19 which engages a fixed contact 19^a or 19^b to close a contact 19—19^a or 19—19^b according as lever L occupies its *a* or *b* position.

Winding 12 of valve V^2 is provided with a circuit which passes from a suitable source of current, here shown as a battery 20, through wire 21, winding 12 of valve V^2 , wire 22, contact 19—19^a of lever L, wire 23, back contact 24—24^b of relay C, and wire 25 back to battery 20. Winding 12 of valve V^2 is also provided with another circuit which is similar to the circuit just traced with the exception that this circuit includes a wire 26 and a front contact 24—24^a of relay C, instead of contact 19—19^a of lever L, wire 23, and back contact 24—24^b of relay C. It will be apparent, therefore, that winding 12 of valve V^2 will become energized when relay C is deenergized and lever L occupies its *a* position, or when relay C is energized regardless of the position of lever L.

Winding 12 of valve V^1 is provided with a circuit which passes from battery 20, through wire 21, winding 12 of valve V^1 , wire 27, contact 19—19^b of lever L, wire 23, back contact 24—24^b of relay C, and wire 25 back to battery 20. It will be apparent, therefore, that winding 12 of valve V^1 will be energized when and only when lever L occupies its *b* position and relay C is deenergized.

It follows from the foregoing that when relay C is deenergized, the braking bars will occupy their non-braking or braking positions according as lever L occupies its *a* or *b* position, but that, when relay C becomes energized, if the braking bars do not already occupy their non-braking positions, they will automatically be moved to their non-braking positions.

The apparatus also includes a series of contacts 29^a, 29^b, 29^c, 29^d, 29^e and 29^f, a series of timing relays S^a, S^b, S^c, S^d and S^e, and a series of locking relays T^a, T^b, T^c, T^d and T^e.

In the particular embodiment of the invention illustrated in the drawing, the contacts 29^a, 29^b, 29^c, 29^d, 29^e and 29^f are controlled by means of treadles 28^a, 28^b, 28^c, 28^d,

28^e and 28^f, respectively, which treadles are placed beside rail 1 in positions where they will be successively engaged and depressed by each car wheel which traverses rail 1. These treadles may be of the usual spring biased type; and each returns to its normal position after being depressed by a car wheel. Each contact is operatively connected with the associated treadle in such manner that when the treadle is not depressed, the contact will be closed, but that, when the treadle becomes depressed by a car wheel, the contact will become opened, and will subsequently remain open during the entire time the treadle is depressed. It will be apparent, therefore, that when a car wheel is passing one of the treadles, the associated contact will be held open for a time interval which depends upon the length of the treadle and the speed of the car. The lengths of the treadles will usually be the same and may be varied as conditions require, but the lengths of the treadles and the spacing between them will preferably be such that the distance from the entering end of one treadle to the leaving end of the treadle next in advance will be less than the distance between adjacent car wheels in the same car truck; and the distance from the leaving end of one treadle to the entering end of the second treadle in advance will be greater than the distance between adjacent car wheels in the same car truck. It will be seen, therefore, that two adjacent treadles will not become depressed at one time, or that one treadle and the second treadle in advance will not become depressed at one time.

The timing relays S^a, S^b, S^c, S^d and S^e are similar relays, and, as here shown, have slow releasing characteristics. Each of these relays is connected with a pair of line wires 30 and 31 over an associated one of the contacts 29, as will be apparent from an inspection of the drawing, and the line wires 30 and 31, in turn, are connected, through a rheostat D, with a suitable source of electromotive force, here shown as a battery B. It will be apparent, therefore, that when none of the treadles 28 is depressed, as will be the case when no car is traversing the stretch of track shown in the drawing, all of these relays will be energized; but that, when a car is traversing the stretch of track shown in the drawing, each time a wheel of the car depresses one of the treadles 28, the associated relay S will become deenergized for an interval of time which depends upon the speed of the car. If the speed of the car is sufficiently slow so that this time interval is longer than the release time of such relay S, this relay will close its back contact 33, but if the car speed is not sufficiently slow so that this time interval is longer than the release time of this relay, this relay will not close its back contact 33. The relays S are so constructed that their

release times may be varied by varying the electromotive force impressed thereon, and it follows that, by causing the arm 38 of rheostat D to engage different taps, the car speed at which the relays S will close their back contacts may be varied; this speed being decreased as the arm 38 of rheostat D is moved toward the left, there being as many different speeds as there are taps on the rheostat D. As will be explained more fully hereinafter, when the contact 33 of any one of the relays S becomes closed, the force applied to the braking bars of the car retarder to hold them in their braking positions is cut off, and it will be seen, therefore, that the rheostat D functions as a speed controller. The parts will usually be so proportioned that when all of the resistance of rheostat D is cut out, the relays S will release when the associated treadles are depressed by the wheels of a car which is travelling at the slowest speed at which it is desired to have cars leave the retarder.

The locking relays T^a, T^b, T^c, T^d and T^e are ordinary quick acting relays, and are each controlled by an associated one of the timing relays S and by one of the contacts 29. Referring to relay T^a, for example, this relay is provided with a pick-up circuit which passes from battery B through line wire 35, the winding of relay T^a, back contact 33 of relay S^a, and line wire 34 back to battery B. Relay T^a is also provided with a stick circuit which passes from battery B through line wire 35, the winding of relay T^a, front contact 36 of relay T^a, contact 29^c, and line wire 30 back to battery B. It will be apparent, therefore, that when relay S^a becomes deenergized and closes its back contact 33, relay T^a will become energized and will close its front contacts 36 and 37. If contact 29^c is then closed as will normally be the case, the stick circuit for relay T^a will be closed, and this relay will therefore remain energized after contact 33 opens until a car wheel subsequently depresses treadle 28^c to open contact 29^c, at which time this relay will again become deenergized. Each of the other relays T is provided with circuits which are similar to the circuits just described for relay T^a. These circuits will be readily understood from an inspection of the drawing without describing them in detail.

The relays T control relay C by virtue of a plurality of parallel pick-up circuits, each of which includes a suitable source of current, here shown as a battery E, and the front contact 37 of a different one of the relays T. It will be seen, therefore, that when all of the relays T are deenergized, relay C will be deenergized, but that when any one of the relays T is energized, relay C will also be energized.

As shown in the drawing, all parts of the

apparatus occupy the positions which they normally occupy when no car is traversing the stretch of track illustrated in the drawing. That is to say, the timing relays S are all energized, and the locking relays T are all deenergized. Arm 38 of rheostat D occupies the position in which all of the resistance of the rheostat is cut in. Relay C is deenergized. Lever L occupies its *a* position, and the braking bars are therefore held in their non-breaking positions.

In explaining the operation of the apparatus as a whole, I will first assume that the operator has moved the braking bars to their braking positions by moving lever L from its *a* to its *b* position, that arm 38 of rheostat D has been moved to a position which will cause the relays S to release at some predetermined speed which I shall term "control" speed, and that a car moving in the direction of the arrow at a speed which is less than control speed, traverse the stretch of track shown in the drawing. Since the car is travelling at a speed which is less than control speed, when the first wheel of the car passes treadle 28^a, contact 29^a will be held open for an interval of time which is longer than the release time of the relays S under these conditions. Relay S^a will therefore close its back contact 33. As a result, relay T^a will become energized and will close its front contacts 36 and 37. The closing of front contact 36 of relay T^a will complete the stick circuit for this relay, and relay T^a will therefore remain energized after relay S^a again becomes energized and opens its back contact 33. The closing of front contact 37 of relay T^a will complete one of the pick-up circuits for relay C, and relay C will therefore also become energized. As previously described, when relay C becomes energized the braking bars will be moved from their braking to their non-braking positions.

When the first wheel of the car next passes treadle 28^b, relay S^b will close its back contact 33, and relay T^b will therefore become energized and will complete its stick circuit, so that this latter relay will remain energized after relay S^b again becomes energized. Furthermore, the energization of relay T^b will complete another circuit for relay C, but since relay C is already energized, it will not be affected, and the braking bars will therefore remain in their non-braking positions.

Likewise, when the first wheel of the car passes treadle 28^c, a similar series of actions will take place. In addition, however, as soon as contact 29^c becomes opened, the stick circuit for relay T^a which was previously closed at this contact will become interrupted, and relay T^a will therefore now become deenergized. The deenergization of relay T^a will interrupt the circuit which was previ-

ously closed for relay C at front contact 37 of relay T^a, but since relay T^b is now energized, relay C will remain energized by virtue of the pick-up circuit including front contact 5. 37 of relay T^b. The braking bars will therefore remain in their non-braking positions.

When the first wheel of the car passes the treadles 28^a and 28^c, the operation of the apparatus will be similar to its operation when 10 this car wheel was passing the treadle 28^c. That is to say, relays T^a and T^c will become energized and will complete their stick circuits, and relays T^b and T^e will become deenergized due to their stick circuits being interrupted at contacts 29^a and 29^c, respectively.

Sometime after the first wheel of the car passes treadle 28^b and before it passes treadle 28^c, the second wheel of the car will pass 20 treadle 28^a, it being apparent that treadle 28^a will not become depressed while treadle 28^b is still depressed, and that treadle 28^c will return to its normal position before treadle 28^a returns to its normal position, because, as 25 previously pointed out, the distance from the entering end of one treadle to the leaving end of the treadle next in advance is less than the distance between adjacent wheels on the same truck of a car, and the distance from the entering end of one treadle to the leaving end of the second treadle in advance is greater than the distance between adjacent car wheels on the same truck of a car. Due to the second 30 wheel passing treadle 28^a, relay T^a will again pick up and will close its stick circuit in the manner previously described so that a circuit for relay C will again become completed at front contact 37 of relay T^a.

When the first wheel of the car passes 40 treadle 28^c, the resultant opening of contact 29^c will interrupt the stick circuits for relays T^a and T^c, so that both of these relays will become deenergized, but since relay T^a is now energized, relay C will remain energized.

45 As the other wheels of the car successively operate the treadles 28, the relays T will become energized and deenergized in the same manner as when the first wheel operated these treadles, there being no time during which 50 all of these relays are deenergized until the car has reached the position in which the last wheel depresses treadle 28^c. When this happens, the subsequent deenergization of relays T^a and T^c will deenergize relay C, and the 55 braking bars will then be restored to their braking positions.

It will be seen, therefore, from the foregoing that when a car which is travelling at a speed which is less than control speed traverses the stretch of track shown in the drawing, the braking bars of the retarder R will move to their non-braking positions as soon as the first wheel of the car passes treadle 28^a and will subsequently remain in their non-braking positions until the last wheel of the

car has depressed treadle 28^c. As a result, no retardation of the car will take place under these conditions.

I will now assume that with the braking bars in their braking positions, and with rheostat D set for the relays S to release at some particular control speed, a car enters the stretch of track shown in the drawing at a speed which is less than this control speed, and that before the car has entirely departed from the stretch, the car accelerates to a speed which is greater than this control speed. Under these conditions, as long as the speed of the car remains below control speed, the apparatus will function in the manner previously described. As soon, however, as the car attains a speed which is above control speed, any of the treadles 28 which subsequently becomes depressed by the wheels of the car will not remain depressed for a sufficient interval of time to permit the associated relay S to release, and as a result, when the car has moved far enough to depress the treadle which controls the stick circuit for the relay T which last became energized, this relay will become deenergized and will deenergize relay C. When this happens, the braking bars will move to their braking positions, and will start to slow-down the car. For example, I will assume that the car speeds up to a speed which is above control speed just as the forward wheel of the car moves into engagement with treadle 28^c, so that relay S^c will not release. Under these conditions, as 90 long as the forward wheel remains in engagement with treadle 28^c, relay T^b, which became energized while the forward wheel was passing treadle 28^b, will be held energized by virtue of its stick circuit, and relay C will 95 therefore also be energized so that the braking bars will occupy their non-braking positions. All of the other relays T will be deenergized. As soon, however, as the forward wheel of the car depresses treadle 28^a, the stick circuit for relay T^a will become interrupted, and relay T^a will therefore become deenergized. When relay T^a becomes deenergized, since all of the other relays T are 100 then deenergized, relay C will also become deenergized, and the braking bars will therefore be moved to their braking positions in the manner previously described.

110 After the braking bars have been moved to their braking positions due to the car having accelerated to a speed which is above control speed, as just described, the braking bars will remain in their braking positions until the car has departed entirely from the stretch, unless the car is again slowed down by the retarder to a speed which is below control speed. If this happens, then as soon thereafter as a wheel of the car passes one of the treadles 28, the relay S controlled thereby will close its back contact 33 which, in turn, will energize the associated relay T. As a 115 120 125 130

result, relay C will again become energized and will cause the braking bars to return to their non-braking positions.

If, with the braking bars in their braking positions and with rheostat D set for the relays S to release at a particular control speed, a car enters the stretch of track shown in the drawing at a speed which is greater than this control speed, the braking bars will remain in their braking positions until the car has been slowed down to this control speed. When this happens, the braking bars will then be automatically moved to their non-braking positions in a manner which will be apparent from the foregoing.

It will be seen, therefore, that with a car retarder constructed in accordance with my invention, the braking action of the retarder will be automatically controlled in accordance with the speed of the car in such manner that the car will leave the retarder at a speed which depends upon the setting of rheostat D.

One feature of car retarder controlling apparatus embodying my invention is that the greater part of the apparatus employed is of standard construction which greatly reduces the cost of installation.

Another feature of car retarder controlling apparatus embodying my invention is that it is simple in operation and requires substantially no maintenance.

Still another advantage of car retarder controlling apparatus embodying my invention is that accurate spacing of the treadles which operate the contacts 29 is unnecessary, and a very simple type of treadle may be employed.

Although I have herein shown and described only one form of car retarder controlling apparatus embodying my invention, it is understood that various changes and modifications may be made therein within the scope of the appended claims without departing from the spirit and scope of my invention.

Having thus described my invention, what I claim is:

1. In combination, a stretch of railway track, a braking bar located adjacent one of the rails of said stretch and movable into engagement with a part of a car traversing said stretch for retarding the speed of the car, a series of contacts arranged to be successively operated by a car traversing said stretch, a series of timing relays one controlled by each contact of the series but the last, a series of locking relays one controlled by each of said timing relays and by a contact of the series located in advance of the contact which controls the associated timing relay, and means controlled by said locking relays for controlling said braking bar.

2. In combination, a stretch of railway track, a braking bar located adjacent one of

the rails of said stretch and movable into engagement with a part of a car traversing said stretch for retarding the speed of the car, a series of contacts arranged to be successively operated by a car traversing said stretch, a series of timing relays one controlled by each contact of the series but the last, a series of locking relays one controlled by each of said timing relays and by a contact of the series located in advance of the contact which controls the associated timing relay, a control relay, means controlled by said locking relays for controlling said control relay, and means controlled by said control relay for controlling said braking bar.

3. In combination, a stretch of railway track, a braking bar located adjacent one of the rails of said stretch and movable into engagement with a part of a car traversing said stretch for retarding the speed of the car, a series of contacts arranged to be successively operated by a car traversing said stretch, a series of timing relays one controlled by each contact of the series but the last, a series of locking relays one controlled by each of said timing relays and by a contact of the series located in advance of the contact which controls the associated timing relay, a manually operable device, and means controlled by said locking relays and by said manually operable device for controlling said braking bar.

4. In combination, a stretch of railway track, a braking bar located adjacent one of the rails of said stretch and movable into engagement with a part of a car traversing said stretch for retarding the speed of the car, a series of contacts arranged to be successively operated by a car traversing said stretch, a series of timing relays one controlled by each contact of the series but the last, a series of locking relays one controlled by each of said timing relays and by a contact of the series located in advance of the contact which controls the associated timing relay, a control relay, means controlled by said locking relays for controlling said control relay, a manually operable device, and means controlled by said control relay and by said manually operable device for controlling said braking bar.

5. In combination, a stretch of railway track, a braking bar located adjacent one of the rails of said stretch and movable into engagement with a part of a car traversing said stretch for retarding the speed of the car, a series of contacts arranged to be successively operated by a car traversing said stretch, a series of timing relays one controlled by each contact of the series but the last, means for varying the operating characteristics of all of said timing relays simultaneously, a series of locking relays one controlled by each of said timing relays and by a contact of the series located in advance of the contact which controls the associated timing

ing relay, and means controlled by said locking relays for controlling said braking bar.

6. In combination, a stretch of railway track, a braking bar located adjacent one of the rails of said stretch and movable into engagement with a part of a car traversing said stretch for retarding the speed of the car, a series of contacts arranged to be successively operated by each wheel of a car traversing one rail of said stretch, a series of timing relays one controlled by each contact of the series but the last, a series of locking relays one controlled by each of said timing relays and by a contact of the series located in advance of the contact which controls the associated timing relay, and means controlled by said locking relays for controlling said braking bar.

7. In combination, a stretch of railway track, a braking bar located adjacent one of the rails of said stretch and movable into engagement with a part of a car traversing said stretch for retarding the speed of the car, a series of contacts arranged to be successively operated by a car traversing said stretch, a series of timing relays one controlled by each contact of the series but the last, a series of locking relays one associated with each of said timing relays and each provided with a pick-up circuit which is controlled by a contact of the associated timing relay, a stick circuit for each of said locking relays controlled by its own front contact and by a contact of said series located in advance of the contact which controls the associated timing relay, and means controlled by said locking relays for controlling said braking bar.

8. In combination, a stretch of railway track, a braking bar located adjacent one of the rails of said stretch and movable into engagement with the wheels of a car traversing said stretch for retarding the speed of the car; a first, a second, and a third contact arranged to be successively operated as the car traverses said stretch, a first timing relay controlled by said first contact and a second timing relay controlled by said second contact, a first and a second locking relay, a pick-up circuit for said first locking relay controlled by a contact of said first timing relay, a stick circuit for said first timing relay controlled by its own front contact and by said third contact, a pick-up circuit for said second locking relay controlled by a contact of said second timing relay, a stick circuit for said second timing relay controlled by its own front contact and by said third contact, and means controlled by said locking relays for controlling said braking bar.

9. In combination, a stretch of railway track, a braking bar located adjacent one of the rails of said stretch and movable into engagement with a car traversing said stretch for retarding the speed of the car, a series of contacts arranged to be successively op-

erated by a car traversing said stretch, a series of timing relays one controlled by each contact of the series but the last, a series of locking relays one associated with each of said timing relays and each provided with a pick-up circuit which is controlled by a contact of the associated timing relay, a stick circuit for each locking relay but the last locking relay of the series of each said stick circuit including a front contact of the associated locking relay and the second contact of the series in advance of the one which controls the timing relay which controls such associated locking relay, a stick circuit for said last locking relay including its own front contact and the last contact of the series of contacts, and means controlled by said timing relays for controlling said braking bar.

10. In combination, a stretch of railway track, a car retarder associated with said stretch, a series of treadles located adjacent one of the rails of said stretch in positions where they will be successively engaged and depressed by each wheel of a car traversing such one rail, a series of normally closed contacts one controlled by each of said treadles, a series of slow releasing timing relays one controlled by each contact of the series but the last, a series of locking relays one associated with each of said timing relays and each provided with a pick-up circuit which is controlled by a back contact of the associated timing relay, a stick circuit for each locking relay of the series but the last, each said stick circuit including a front contact of the associated locking relay and the second contact of the series of contacts in advance of the contact which controls the associated timing relay, a stick circuit for the last locking relay of the series including its own front contact and the last contact of the series of contacts, a control relay, a plurality of circuits for said control relay one controlled by a front contact of each of said locking relays, and means controlled by said control relay for controlling said braking bar.

In testimony whereof I affix my signature.

JOHN W. LIVINGSTON.
